UNITED STATES PATENT OFFICE.

ELDEN H. BEAN, OF KITCHENER, ONTARIO, CANADA.

DISAPPEARING BED.

Application filed April 20, 1927. Serial No. 185,239.

My present invention relates to beds and has particular reference to that type of furniture known as a disappearing bed. In the embodiment which I have herein disclosed the bed is stored within a hollow mantel structure in the front wall of which there is a fire-place opening and the walls of the fireplace back of the opening are adapted to collapse whenever the bed portion is lowered to use the bed.

I am aware of the fact that numerous methods and structures have been devised to provide disappearing beds for the purpose of economizing the floor space in smaller or restricted apartments, and in most of these instances it has been necessary to build a large chamber or compartment into which the bed is moved and stored when not in use. It has also been the practice to mount the bed upon a double-door, which, upon being opened, will permit the use of the bed. The chief objection to most of the prior structures has been that it is always necessary to construct or build into the apartment a special chamber of no small dimensions to accommodate the bed, which chamber, while it may be conveniently utilized for the storage of clothing, trunks, and other articles, nevertheless reduces the size of one or more of the rooms adjacent thereto. Most apartments are provided in one or more of its rooms with a mantel and fireplace which usually extend into the room a small distance and are more or less ornate, and in designing my invention I have therefore utilized the space back of the front wall of the mantel and below its shelf for the storage of the bed, thus providing a convenient article of furniture without detracting from the appearance of the room and without diminishing its floor or wall space thereof. As only the front wall of the mantel structure is movable to use the bed it is unnecessary to remove articles from the mantel shelf when the bed is lowered, and as fuel is seldom burned in the fireplace it is only necessary to remove artificial logs and fire-dogs when the bed is to be used.

My invention has numerous objects in view, among which are the provision of a disappearing bed that is novel in construction, economical to manufacture, effective in

performing the function for which it is designed, and which is compact in the arrangement and disposition of its parts. I prefer to carry out my invention in substantially the manner hereinafter fully described and as more particularly pointed out in the appended claims, reference being herein made to the accompanying drawings that form a part of this specification.

In the drawings:

Figure 1 is a vertical front elevation of a mantel and fire-place with my invention incorporated therein.

Figure 2 is a vertical section taken on line A—A of Figure 1, looking in the direction of the arrows and showing the structure in closed position.

Figure 3 is a fragmental sectional detail taken on line B—B of Figure 2, looking in the direction of the arrows and drawn to a larger scale.

Figure 4 is a vertical transverse section taken on line C—C Figure 5 looking in the direction of the arrows and showing the relative positions of the parts of the bed, the mantel, and the fireplace walls when the structure is opened to use the bed.

Figure 5 is a vertical front elevation of the structure illustrated in Figure 1 when the same is opened as in Figure 4.

Figure 6 is a fragmental view, partly in section on line D—D of Figure 4, showing in detail the roller and guide devices.

These drawings are, in a sense, merely schematic for the purpose of illustrating a typical or preferred embodiment of my invention, and in said drawings I have employed the same reference characters to designate like parts wherever they appear throughout the several views.

A conventional mantel and fire-place are illustrated in the drawings, the mantel consisting of a horizontal shelf 10, supported upon vertical end or side walls 11 and 12 the lower portions of which are widened as at 14 to provide the shoulders shown in Figure 4, and said shelf and end walls are connected at their rear edges by a vertical back or rear wall 13, which may be the wall or partition of the building or apartment in which the structure is erected or may be the back of the compartment in the event the structure is manufactured as a unit or

article of furniture. Across the front, and below the shelf, there extends a movable wall 15 that may be lowered when desired and is provided with a suitable shaped fireplace opening 16 that preferably extends down practically to the floor or hearth and may be more or less ornate as desired.

The interior fireplace is formed by means of converging side walls 17 that are connected to their forward vertical edges to the respective vertical edges of the opening 16 by means of hinges 18 and the upper edges of these walls are preferably cut oblique so as to extend downwardly towards their rear edges as seen in Figures 1 and 2 so as to support a sloping top member 19 that is connected by hinges 20 along its forward edge to the upper edge of the fireplace opening 16. This creates a perspective aspect to the fireplace and permits radiation of the heat into the room. This arrangement of the walls 17 and 19 permit the latter to be lifted slightly and the side walls 17 collapsed to flat positions across the fireplace opening and then the top member 19 is laid flat against the backs of said side walls 17 substantially in the manner shown in Figure 4. The top wall 19 is notched or shouldered as at x to insure the desired positioning of the upper edges of the side walls as shown in Figure 3.

The front wall 15 of the hereinbefore described structure as a lateral extension 21 extending inwardly along its upper longitudinal edge, which extension projects into the space below the shelf 10, and there are also lateral extensions 22 projecting inwardly from the vertical side portion of front wall 15 that extend into the space below the shelf and alongside the vertical side walls 11 and 12 of the mantel structure. These extensions 21 and 22 are less in width than the end walls 11 and 12 but extend deeper into the space behind the front wall than the fireplace walls. The bed springs 23 are suitably connected to the inner edges of these extensions so that the bed will be positioned entirely back of the fireplace wall so that when the structure is opened as in Figure 4, the fireplace walls being collapsed, there is ample space above said walls to permit of the yielding of the spring to the limit of their flexibility. In order to obscure the bed from being seen from the front of the fireplace and mantel I have provided a back wall 24 for the fireplace opening which, like the other walls of the fireplace opening may be made from heat-insulating and fireproof material. This back wall 24 is supported in a pendent manner either from the springs 23 or by the cable y connected to the upper extension 21 of the front wall of the mantel so that under normal conditions, when the bed is closed, said wall 24 will engage the rear edges of the fireplace

walls 17 and 19, and when the structure is opened and the fireplace walls collapsed said back wall will rest upon the folded walls in the manner shown in Figure 4.

There is preferably a hearth or base 25 that extends under the mantel walls and is provided adjacent each end with concave tracks or grooves 26 that extend transversely inwardly from near the forward portion of the hearth. At each end of the lower portion of the front wall there are rollers 27 that are mounted in angular brackets 28, in the manner shown in Figure 6 and guard rails 29 extend from the front to the rear of grooves 26 and are positioned between the brackets 28 and above the rollers 27 so as to retain and guide the structure in these tracks or grooves. Above the rollers and extending inwardly along the adjacent edge of the front wall (which is the bottom wall in the closed position) is a lateral extension 30 similar to the extensions previously described except that it is either formed in a plurality of pieces or is provided with slots 31 into which the guard rails 29 will be positioned when the structure is opened. When the bed and front wall structure are moved from vertical to horizontal positions the rollers 27 will permit the pivoting and sliding movement and there are also provided rollers 32 against which adjacent edges of the side extensions 22 engage, said rollers being mounted upon end walls 11 and 12 of the mantel structure. Suitable counter balancing or equalizing means are provided in the form of a coiled spring 33 extending horizontally along the corner formed by the mantel 10 and rear wall 13, the ends of the spring being respectively connected with adjacent ends of cables 34 that pass over pulleys 35 in the corners of the back structure and then around guide rollers 36 to a convenient portion of the bed and front wall structure where they are anchored at a suitable place by means of the pins or the like 37. Ornamental rotatable knobs 38 provide rests or supports for the outer edge of the movable portion of the structure when it is in its lowered position while the rear portion is supported upon the rollers 27. The shanks of these knobs protrude through the front wall 15 and are provided with wings 39, upon their inner ends so that said shanks may be rotated by reaching through apertures 40 in extension 21 when the structure is opened. Suitable cables or wires 41 are connected to the shanks of knobs 38 and at their other ends are connected to latching devices 42 which lock the movable parts in their opened position and prevent them accidentally closing under the pull of the spring tension of the equalizer or counterbalance and also maintain the movable structure in closed or raised position when the bed and front wall are vertically disposed.

From the foregoing it will be seen that the bed, mantel and fireplace parts may if desired be manufactured as a unit and installed in an apartment where it is necessary 5 to have additional sleeping accommodations, or the mantel may be built during the erection of the building and therefore form a permanent portion thereof, after which the disappearing bed portions may be installed 10 when the building is being finished with the trim and other final work therein. In connection with the foregoing it will also be noted that the length and height of the structure represents the respective length 15 and width of the bed itself which will be of a size to readily accommodate one or more persons thereon. In the event gas-logs are placed in the fireplace connection thereof is made with the gas pipe by means of flexible tubing of sufficient length to permit the logs to be removed from the fireplace and placed alongside the mantel before lowering 20 the bed.

What I claim is:—

25 1. A device of the character described comprising a mantel structure having a fireplace opening in the vertical front wall thereof, an open rigid bed mounted on and carried by the front wall, walls hinged to the 30 edges of the fire-place opening and extending inwardly and back of the fireplace opening whereby to provide a recess and to render the bed invisible through said opening, said hinged walls adapted to be folded upon each 35 other upon the lowering of the bed, and hinges permitting the movement of the front wall to lower the bed to a horizontal position.

2. A device of the character described comprising a mantel having a front wall hinged 40 at its lower portion and provided with a fireplace opening, a bed connected to and movable with said front wall, and fireplace walls hinged to the edges of said opening and normally extended towards the bed 45 and adapted to move away from the bed when the mantel front wall is lowered to a horizontal position whereby to permit the yielding of the bed springs when the bed is in use.

50 3. A device of the character described comprising a mantel structure having a fireplace opening in the vertical front wall thereof, a bed connected to said front wall, pivotal means at the lower portion of the front wall 55 that is adapted to lower the bed to a horizontal position, and a plurality of movable walls disposed back of the fireplace opening to form a walled recess and adapted to move to

collapsed position to close the opening when the front wall is lowered. 60

4. A device of the character described comprising a mantel structure having a front wall hinged at its lower portion and provided with a fireplace opening, a bed connected to and movable with said front wall, 65 a plurality of partition walls hinged at their forward edges to the edges of the fireplace opening and providing a recess back of said opening and shielding the bed, said partition walls adapted when the mantel wall is 70 lowered to collapse flat upon each other whereby to accommodate the yielding of the bed springs when in use.

5. A device of the character described comprising a mantel structure having an 75 opening in the vertical front wall, top and side fireplace walls hinged to said front wall at the respective portions of the opening, a rear fireplace wall pendently hung from the upper portion of the mantel structure, and 80 a bed frame connected to the movable portion of the mantel structure and normally in a vertical plane back of the rear fireplace wall, whereby when the front wall of the mantel structure is moved into a horizontal plane said bed structure will be correspondingly positioned and the fireplace walls will be collapsed flat upon each other below the bed structure. 85

6. A device of the character described 90 comprising a mantel structure having a hinged portion adapted to be moved to a horizontal position, a bed carried by said hinged portion, and a fireplace forming a 95 part of said hinged portion, the walls of the fireplace hinged to the edges of the fire place and adapted to be moved away from the bed and collapsed to permit the yielding of the bed springs in use.

7. A device of the character described 100 comprising a hollow compartment open at the front, a hinged wall closing the front and provided with an opening extending upwardly from its lower edge, walls extending into the compartment and hinged to the edges of said opening, extensions on the edges of said front wall and normally positioned in said compartment, bed-springs connected to and supported by the inner edges of said extensions, and a wall back of said 105 collapsible walls and hung pendent from an upper portion of the structure. 110
